(57) **CLAIM**

We claim the ornamental design for a writing instrument, as shown and described.

DESCRIPTION

FIG. 1 is a upper perspective view showing our new design for a writing instrument;

FIG. 2 is a first side view showing the design of FIG. 1;
FIG. 3 is a second side view showing the design of FIG. 1;
FIG. 4 is a third side view showing the design of FIG. 1;
FIG. 5 is a fourth side view showing the design of FIG. 1;
FIG. 6 is a top view showing the design of FIG. 1;
FIG. 7 is a bottom view showing the design of FIG. 1; and,
FIG. 8 is a side view showing the design of FIG. 1 in an alternate configuration.

In FIGS. 1-8, the broken lines illustrate portions of the writing instrument that do not form a part of the claimed design.

1 Claim, 5 Drawing Sheets
